UNITED STATES PATENT OFFICE.

ELMER E. SANBORN, OF LYNN, MASSACHUSETTS.

MACHINE FOR GRADING PATTERNS.

1,413,065.

Specification of Letters Patent. Patented Apr. 18, 1922.

Application filed January 6, 1921. Serial No. 435,382.

To all whom it may concern:

Be it known that I, ELMER E. SANBORN, a citizen of the United States, and resident of Lynn, county of Essex, State of Massachusetts, have invented an Improvement in Machines for Grading Patterns, of which the following description, in connection with the accompanying drawing, is a specification, like characters on the drawing representing

10 like parts.

This invention relates to machines for forming patterns from a master pattern and while it is capable of a wide variety of uses, yet it has special advantages when used in forming shoe patterns. In cutting or forming shoe patterns it is customary to employ a master pattern and then from this master pattern to cut or form a plurality of similar patterns of different sizes for different sizes

20 of shoes. This operation is commonly referred to in the trade as "grading patterns." The machines which are used for this purpose of grading patterns comprise a cutting or scribing element, a work holder for holding the sheet of material from which the pattern is to be cut, means to support a master pattern, a tracer or follower adapted to be moved around the edge of the master pattern and means operable by the movement of the

30 tracer to cause the cutter or scribing tool to cut from, or mark on, the sheet of material a pattern similar to the master pattern.

One of the objects of my present invention is to provide a novel grading machine in which the master pattern and the cutter or scribing tool are held stationary relative to each other during the operation of the machine while the material from which the pattern is to be cut is given a movement relative to the tool, but is so controlled by the stationary master pattern as to cause the tool to cut from, or form on, the sheet material the desired pattern.

Another object of my invention is to provide a grading machine in which the cutter or scribing tool and its operative parts are carried by a support that is entirely separate from the means that support the master pattern and the work, so that the said tool may be moved into any convenient position relative to the other parts of the machine without affecting in any way the operation thereof.

Another object of the invention is to provide a novel grading machine by which it is possible in the making of any pattern to produce a greater variation from the master

pattern in one direction than in a direction perpendicular thereto. This feature of the invention is useful where it is desired to grade a pattern of a shoe vamp for instance, by producing a pattern which differs more from the master pattern in the direction of the length than in the direction of the width.

Other objects of my invention are to provide an improved means for supporting the master pattern, to provide an improved mechanism for producing the desired movement in the work support and otherwise to improve machines of this type, all as will more fully be hereinafter set forth.

In order to give an understanding of my invention I have illustrated in the drawings a selected embodiment thereof which will now be described, after which the novel features will be pointed out in the appended claims.

In the drawings:

Fig. 1 is a front view of a grading machine embodying my invention,

Fig. 2 is a top plan view thereof,

Fig. 3 is a side view of the scribing tool,

Fig. 4 is an enlarged section on the line 4—4, Fig. 2,

Fig. 5 is an enlarged section on the line 5—5, Fig. 3,

Fig. 6 is an enlarged section on the line 6—6, Fig. 2,

Fig. 7 is a view of the tracer or follower,

Fig. 8 is an enlarged section through the work clamp on the line 8—8, Fig. 2,

Fig. 9 is a section on the line 9—9, Fig. 6,

Fig. 10 is a fragmentary plan view showing the means for clamping the master pattern to its holder.

Fig. 11 is a side view partially in section, showing the punch which is used for forming the apertures in the master pattern,

Fig. 12 is a plan view of Fig. 11,

Fig. 13 is a vertical section through the punch,

Fig. 14 is an enlarged fragmentary sectional view showing the manner in which the carriages are supported,

Fig. 15 is a section on the line 15—15, Fig. 14,

Fig. 16 is a plan view of the lever connection 42,

Fig. 17 is a section on the line 17—17, Fig. 2,

Fig. 18 is an enlarged view of the indicator for indicating different sizes.

The machine is intended primarily for cutting patterns from, or marking patterns on material having a flat face, and while the character of the material is not important so far as the invention is concerned, provided it has a flat face, yet for the sake of illustrating the invention, I have shown material in the form of sheet material. I will therefore for convenience hereinafter refer to the material as sheet material, but with the understanding that this expression is not used in a limiting sense but merely as illustration of one kind of material on which the machine can operate.

15 The material from which the pattern is to be cut is supported in a work-supporting mechanism or jack indicated generally at 1. This work-supporting mechanism will be constructed to hold properly the particular material being used, and where such material is sheet material as herein shown, I will preferably make said work-supporting mechanism with suitable jaws between which the sheet material may be clamped.

25 The pattern is cut from, or marked on, the sheet material by means of an element which I will hereinafter refer to as an outlining tool or outlining mechanism because it forms on the sheet material the outline 30 of the desired pattern. So far as the invention is concerned this outlining tool might operate either to cut the pattern from the sheet material or mark it thereon. I prefer, however, to employ an outlining 35 tool of the type which will cut the pattern from the sheet material. The outlining tool may assume various forms without departing from the broad principle of my invention. I have herein illustrated, however, a form of outlining tool which involves a rapidly reciprocating punch 7 adapted to punch in the sheet material a multitude of apertures which overlap each other to such an extent as to form a slot. The 40 outlining tool or mechanism is indicated generally at 2 and it is supported upon a frame which is entirely independent from that which supports the work-holding means 1. The particular construction of the outlining 45 mechanism will be presently given in detail.

50 The master pattern is supported on a stationary pattern support indicated generally at 3. In the drawings I have illustrated a master pattern 4 for a shoe vamp, but, of course, the particular shape and contour of the pattern 4 is immaterial. As stated above, the master pattern 4 is fixedly secured to its stationary support 3 and a 55 tracer, indicated at 5, is employed which is designed to trace around the edge of the pattern 4, as usual in machines of this character. The present invention involves means 60 which is controlled by the movement of the tracer around the pattern to give the work 65

support 1 a movement relative to the outlining tool, thereby to cause the latter to form on or from the sheet material 6 a pattern which is similar to the master pattern 4, but which may be either of the same size 70 as the master pattern or of a different size depending on the adjustment of said means. In other words, in my improved machine the master pattern 4 and the outlining tool are stationary relative to each other and the 75 forming of the pattern from the sheet material is accomplished by moving the sheet material relative to the outlining tool.

The work supporting means 1 and the pattern support 3 are carried by a suitable 80 base frame, indicated generally at 8, and it may have any appropriate construction. This frame is shown as having a platform or portion 9 which constitutes the support for the master pattern. The particular 85 means employed for attaching the master pattern to the support will be presently described.

The work supporting element 1 is supported on the main frame 8 through four 90 movably mounted carriages superposed one on the other, two of which are constructed to move longitudinally of the frame and the other two of which are constructed to move transversely of the frame. These carriages comprise a lower carriage 10 movably mounted on ways 11 formed on the base frame 8 and extending transversely thereof, so that the lower carriage 10 can only move transversely; another carriage 12 100 which is mounted on the lower carriage 10 to move longitudinally thereof; a carriage 13 which is mounted on the carriage 12 and is adapted to be moved longitudinally thereof; and, an upper carriage 14 which is 105 mounted on the carriage 13 and is arranged to be moved transversely thereof.

The work holding member 1 is sustained on this upper carriage 14. Any suitable means may be provided for guiding the carriages one on the other. I prefer, however, to employ a special form of ball bearings between the various carriages. The base frame 8 and each of the carriages is provided with V-tracks or grooves 15 in which 110 are received a plurality of balls 16 that are sustained in and properly spaced by a cage 17, the latter being a thin strip of metal having apertures therein to receive the balls, so that the balls project both above 115 and below it. Each of the carriages is provided on its under face with V-grooves to receive the balls. These ball bearings are preferably placed at the ends of each carriage and the V-grooves on the under side 120 of each carriage are preferably cut away at the central portion of the carriage as shown at 105 to such an extent as to be out of contact with the balls. The portions 106 at each end of each V-groove which 130

<p

bears against the balls is preferably of a sufficient length to receive two balls only, and as a result each carriage is supported at each corner on not more than two balls.

- 5 This construction prevents the possibility of the carriages having any rocking motion due to a high ball in the center and results in maintaining each carriage accurately in alignment. As any carriage is moved the cages 17 for the balls on which said carriage is supported will travel with the balls at one-half the speed of the carriage.

- 10 The tracer 5 is carried on the carriage 12. The movement of the carriage 12 on the carriage 10 longitudinally of the frame permits the tracer to have a longitudinal movement and the transverse movement of the carriages 10 and 12 on the base 8 permits the tracer to have a transverse movement.
- 15 These two movements combined permit the tracer to move in any direction and enable it to follow around the contour of any pattern 4.

- This tracer is shown as carried on a stem 18 which is screw threaded in an arm 19 extending from the carriage 12, said arm having a hand piece 20 by which the carriage 12 may be manipulated. The stem 18 of the tracer is mounted in the arm 19 for vertical adjustment, this being provided for by making the stem with a screw threaded portion 21 which has screw threaded engagement with the arm 19 and providing said stem with a handle 22 by which it may be turned, thereby to raise and lower it in the arm 19. The tracer is formed with an annular groove 23 in which the edge of the pattern 4 is received, said groove acting as a guide so as to better maintain engagement of the tracer with the edge of the pattern. When the tracer is not in use it can be raised into the position shown in Fig. 7. When it is to be used the handle 22 is turned so as to screw the stem 18 downwardly to bring the groove 23 opposite the edge of the pattern 4 and then by manipulating the handle 20 the tracer may be carried around the edge of the pattern.

- Suitable operative connections are provided between the upper carriage 14, on which the work supporting member 1 is sustained, and the carriage 12 by which the movements of the carriage 12 are transmitted to the carriage 14 thereby causing the work to have a movement corresponding to that of the tracer in following the edge of the pattern. These operative connections are such that the movement which is given to the work holder may be either a duplicate of the movement of the tracer, or may be a similar movement but of greater or less amplitude. When the connections are arranged so that the movement of the work holder is the same as that of the tracer in following the pattern 4, then the pattern

which is cut from the sheet 6 will be a duplicate in size of the master pattern, but if these operative connections are adjusted so as to give the work support a movement similar to that of the tracer but of greater 70 or less amplitude, then the pattern which is cut will be similar to the master pattern but of a larger or smaller size.

When these operative connections are adjusted so as to cause the pattern which is 75 cut from the sheet 6 to be a duplicate in size of the master pattern, the upper carriages 13 and 14 will have no movement relative to each other, and the entire movement which is given to the work support will be 80 that produced through the lower carriages 10 and 12. I have therefore chosen to refer to these lower carriages 10 and 12 as duplicating carriages because they are the ones which are operative to duplicate the 85 master pattern.

On the other hand where these operative connections are adjusted so as to produce a pattern which is similar to the master pattern but different therefrom in size, then the 90 upper carriages 13 and 14 will have a movement relative to the lower carriages, and as these upper carriages come into play when patterns are being graded, I have chosen to refer to these upper carriages 13 and 14 as 95 grading carriages.

The operative connections above described by which the carriages are given their movement comprise one connection between the longitudinally movable duplicating carriage 100 12 and the longitudinally movable grading carriage 13 which controls the longitudinal movement of the work support relative to that of the carriage 12, and another connection between the longitudinally movable 105 grading carriage 13 and the transversely movable grading carriage 14 which controls the transverse movement of the work support relative to the carriage 12.

The first of these connections is in the 110 form of a lever 24 which is pivoted to the carriage 12 at 25 and which is also pivotally connected at 26 to a fulcrum block 27 that is slidably mounted on ways 28 that extend transversely of the main frame. This fulcrum 26, therefore, can move in a transverse direction, but has no movement longitudinally of the frame. The lever 24 is connected to the longitudinally movable grading carriage 13 by means of a link 29, one 120 end of which is pivoted to the carriage 13 as shown at 30 and the other end of which is pivotally connected at 31 to a block 32 that is slidably mounted on the lever 24. The portion of the lever 24, on which this block 125 is mounted, is curved, with a radius of curvature equal to the length of the link 29. The block 32 can be shifted on the lever 24 to either side of the pivotal point 25.

Since the pivot 26 has no movement lon- 130

itudinally of the frame and since said lever is pivoted at 25 to the longitudinally movable carriage 12 it will follow that any movement of the carriage 12 longitudinally of 5 the frame will cause a swinging movement of the lever 24 and because of the fact that the pivot 26 is carried by the slidable block 27 this movement will be in no wise affected by any transverse movement of the carriage 10 12. If the block 32 is placed directly over the pivot 25 then the carriage 13 will move in unison with the carriage 12 because the effect will be the same as if the link 29 were 15 pivotally connected directly to the carriage 12. If, however, the block 32 is adjusted out of line with the pivot 25 into the position shown in Fig. 2 then the swinging movement of the lever 24, due to movement of the carriage 12 longitudinally of the frame, will 20 operate to give the carriage 13 an increment of motion over that of the carriage 12, such increment being greater or less, depending upon the distance which the block 32 is from the center 25. On the other hand, if the 25 block 32 is shifted to the opposite side of the center 25 from that illustrated in Fig. 2, then the carriage 13 will have a decrement of movement under that of the carriage 12, the amount of such decrement depending on the 30 position of the block 32. Hence, by properly adjusting the block 32 the carriage 13 will be given a movement longitudinally of the frame either greater or less than that given to the carriage 12 by a predetermined 35 amount dependent on the position of the block 32.

Suitable means are provided for locking the block 32 in any adjusted position on the lever 24, but a convenient mechanism for 40 this purpose is illustrated in Figs. 6 and 9. The arm 24 is provided with a groove 33 in its upper face in which is received a notched bar 34. The block 32 has a latch 35 pivoted thereto at 36, which latch extends across the 45 top of the lever 24 and is adapted to engage in any one of the notches of the bar 34. This latch 35 extends through a slot 37 formed in the block 32 and is thus prevented from lateral movement. It is shown as acted 50 upon by a spring 38 which normally holds it in operative position. The block 32 carries a stud 39 on which is rotatably mounted a cam 40 having a hand wheel 41 connected thereto by which it may be turned. The 55 cam is situated so that the end of the latch 35 projects over it and when said cam is situated so that the low part thereof comes opposite the latch, then the latch is permitted to occupy one of the notches of the bar 60 34, but by giving the cam a part rotation the high part thereof will elevate the latch and thus lift it from the notch in the bar 34, thus unlocking the block so as to permit it to be shifted longitudinally of the lever 24.

65 The connection between the upper trans-

versely movable grading carriage 14 and the longitudinally movable grading carriage 13 is similar to that above described and operates in a similar manner. It comprises a lever 42 which is pivoted at 43 to a support 44 rigid with, but depending from, the carriage 13. One end of this lever 42 is pivoted at 45 to a block 46 which is slidably mounted on ways 47 extending longitudinally of the frame. The pivot 45, therefore, can move 70 longitudinally with the carriage 13, but is prevented from movement transversely of the frame. Any movement of the carriage 13 transversely of the frame will, therefore, give swinging movement to the lever 42 about its pivot 45. The upper carriage 14 is connected to this lever 42 by means of a link 48, said link being pivoted to the carriage 14 at 49 and also being pivotally connected to a block 50 which is slidably mounted on the lever 42. The connection between the block 50 and the lever 42 is similar to that shown in Figs. 6 and 9 except that the notched bar 34 is placed on the under side of the lever 42 instead of on top thereof. 80 With this arrangement it will be evident that when the block 50 is adjusted so as to be directly over the pivot 43, then any swinging movement of the lever 42, due to transverse movement of the carriage 13, will not affect the carriage 14, and the two carriages 13 and 14 will have no movement relatively to each other. On the other hand, if the block 50 is moved into the position shown in Fig. 2, then any swinging movement of the 85 lever 42, due to transverse movement of the carriage 13, will give the carriage 14 an increased motion over that of the carriage 13, the amount of increase depending on the position of the block 50 relative to the pivot 90 43. On the other hand, when the block 50 is shifted to the right of the pivot 43 shown in Fig. 2, then the swinging of the lever 42, due to transverse movement of the carriage 13, will cause the carriage 14 to have a less 95 transverse movement than said carriage 13. Thus the combined action of the levers 42 and 24 will result in giving to the carriage 14, and the work support sustained thereby, 100 a movement similar to, but of a greater or less amplitude than that of the carriage 12 depending on the adjustment of the blocks 32 and 50.

When the device is used for grading shoe patterns the master pattern is secured to the pattern support 3 and the blocks 32 and 50 will then be adjusted to correspond to the size of the pattern which it is desired to form from the sheet material 6. If, for instance, the master pattern corresponds to size 8 and it is desired to form a pattern for an $8\frac{1}{2}$ shoe, or a 9 shoe, or a $9\frac{1}{2}$, then the blocks 32 and 50 will be adjusted the proper distance away from the centers 25 and 43 to produce the pattern of the desired size. The 105 110 115 120 125 130

notches in the bar 34 will preferably be so spaced as to correspond to half sizes and, therefore, an adjustment of either block 32 or 50 one notch away from the center in one direction will produce a pattern a half size larger; two notches away will produce a pattern a full size larger, etc. After the adjustment has been made then the tracer is placed against the edge of the master pattern 4 and the scribing tool is set in operation and the tracer is carried around the edge of the master pattern, such movement giving a similar movement to the carriage 12. This movement of the carriage 12 is transmitted through the connections above described to the carriage 14 in such a way that the carriage 14 will have a movement similar to the carriage 12, but greater in amplitude in all directions, with the result that the pattern, which is cut or formed from the sheet material, will be similar to the pattern 4, but larger than it by an amount determined by the adjustment of the blocks 32 and 50. By similar adjustment of the blocks in the opposite direction a pattern smaller than the master pattern but similar thereto may be formed.

In order to assist the operator in effecting a proper adjustment of the blocks 32 and 50 I propose to equip each lever with a gauge device. This is in the form of a graduated disk 51 pivotally mounted at 52 on the lever, (24 or 42), and having a cord or flexible connection 53 wound on the edge thereof and connected to the link (29 or 48). Each disk 51 is acted on by a spring 151 which normally keeps the connection 53 taut. Each disk is provided with graduations 55 corresponding to the sizes and half sizes of shoes and each lever carries an indication mark 54 which co-operates with the graduations 55 to indicate the adjustment of the block 32 or 50. As either block is shifted longitudinally of its lever the disk 51 will turn on its pivot and the particular graduation mark which is opposite the indicating mark 54 will indicate the size of shoe for which the machine is set. If, therefore, it is desired to form a pattern for a $7\frac{1}{2}$ shoe, then the blocks 32 and 50 are simply adjusted until the $7\frac{1}{2}$ graduation comes opposite the indication mark 54.

I have above described the operations of duplicating the master pattern and of grading patterns from the master pattern that is, the operation of producing a pattern similar to the master pattern but of a different size in all directions.

It sometimes happens that it is desirable to produce a pattern which is similar to the master pattern in one direction but is longer or shorter than said master pattern in the opposite direction. For instance, in the case of the vamp pattern shown in the drawings, it is sometimes necessary to produce a pat-

tern which is the same width as the master pattern but is longer. Then again in producing patterns for shoe uppers, it is sometimes desirable to provide a pattern having the same height as the master pattern but one which is larger around. In order to provide for these operations, I have embodied in my machine means by which these variations in the pattern from the master pattern can be obtained. For this purpose each of the levers 24 and 42 is made in two sections, which are pivoted together and can be adjusted angularly relative to each other. In case of the lever 24 for instance, it is formed with an arm or extension 107 and is also provided with the forked section 108, which is pivoted to the lever at the point 52. This lever section 108 is provided with a sector 109 and also with the extension 110 which carries the pivot 26. The two sections of the lever can be turned relatively to each other about the pivot 52, and when this operation is carried out the result will be that the curved portion of the lever 24 will be turned into a different angular position about its pivot 25. For normal operation of the machine the extension 107 will be adjusted into what I will term for convenience a neutral position. If it is desired to produce a pattern which is longer or shorter than the master pattern but of the same width, then the lever extension 107 will be adjusted to one side or the other of the neutral position thereby producing in the longitudinal, movable, grading carriage either an added or a decreased longitudinal movement which will result in producing a pattern that is either longer or shorter than the master pattern.

The lever 42 has a similar construction and when the extension 111 thereof is adjusted to one side or the other of the neutral position, the result will be a change in position of the upper duplicating carriage 14 which will produce a pattern that is either wider or narrower than the master pattern, depending on the adjustment. These compensating means, therefore, enables me to produce patterns which vary from the master pattern a greater amount in one direction than in the other.

Any suitable means may be employed for locking the arm extensions 107 to the sectors 109. I have herein shown a device similar to that which is employed for locking the blocks 32 to the levers 42 or 24. Each sector is provided in its upper face with a plurality of notches 112 and each extension 107 is formed with a latch 212 adapted to enter in one of the notches. This latch may be elevated by means of a cam 213 which is similar in construction to the cam 40, so that by giving the cam 213 a partial rotation the latch will be raised, thereby unlocking the extension 109 from the sector, and when the

extension has been adjusted properly relative to the sector, a return of the cam to its normal position will allow the latch to again re-engage one of the notches 112.

5 The work-holding means which is indicated generally at 1 may have any suitable construction adapted to support the material from which the pattern is to be cut. When such material is in the form of sheet material the work-holding means may conveniently be in the form of jaws between which the sheet may be clamped. The work support herein shown comprises two jaws 56, 57 between which the sheet 6 may be placed 10 and also means for clamping the sheet firmly between the jaws. The lower jaw 57 is shown as having a barbed bed plate 58 and the upper jaw is provided with a clamping member 59 which can be clamped against the sheet 6 to force it firmly against the barbed bed plate 58. This clamping member 59 is shown as provided with a stem 60 slidably mounted in the jaw 56 and acted on by a spring 61 which normally tends to hold it 15 elevated. The jaw 56 has a cam shaft 62 journaled therein which carries a cam 63 bearing on the stem 60. This shaft 62 is provided with a handle 64 by which it may be turned and by rotating the shaft in either 20 direction from the position shown in Fig. 8 the clamping member 59 will be depressed, thus clamping the sheet material firmly against the barbed bed plate 58. The clamping member 59 is provided with guiding 25 pins 65 operating in apertures formed in the jaw 56 and serving to guide the clamping member in its movement.

30 66 is a stripper element carried by the jaw 57 for stripping the sheet material 6 from the barbed bed plate when the clamp is released. This stripper is in the form of a plunger acted on by a spring 67 which tends normally to elevate it, the spring-impelled movement of the stripper being limited by 35 a pin 68 operating in a slot 69 formed in the stem.

40 The work supporting element 1 is shown as having two arms 70 extending from the lower jaw and which constitute a support 45 for the sheet material if the latter is relatively large. This work supporting element is shown as pivotally mounted on the carriage 14 so that the jaws can be turned into different angular positions.

55 The carriage 14 is provided with a cross bar 71 on which the work holding jaws are supported. This cross bar 71 has a clamping bolt 72 extending vertically therethrough which screws into the lower jaw 57 60 and which is provided with a handle 73 by which it may be turned. When the clamping screw 72 is loosened, then the jaws can be shifted into any desired angular position and they will be retained in such position 65 by tightening the clamping screw 72.

As stated above the outlining tool herein illustrated is in the form of a vertically reciprocating punch 7. This punch co-operates with a die 74 carried by an arm or bar 75. The punch 7 is mounted for vertical reciprocation in a guiding sleeve 76 which is carried by a head 114 at the end of an arm 77, which is secured to the arm or member 75 at one end as shown at 78. The punch 7 may be given its vertical reciprocations in any suitable way. I have herein shown it as operated from a motor 79 which is mounted on the arm or bar 77. This motor is belted to a shaft 80 by means of a driving belt 81, said shaft having a pulley 82 thereon to receive the 75 motor. The shaft 80 is rotatably mounted in a suitable bearing 83 carried by the arm 77 and said shaft has a crank pin 84 mounted eccentrically therein to which is pivotally connected one end of a link 85, the other end 80 of said link being connected to a lever 86 which is pivoted at 87. This lever is provided with a slot 88 that receives a pin 89 extending from the punch 7. The rotation of the shaft 80 will thus oscillate the lever 85 and the latter will give reciprocating movement to the punch 7.

90 The punch may be raised and lowered so as to carry it into inoperative position above the sheet, or into operative position where 95 it will act on the sheet.

95 This is provided for by supporting the pivot 87 for the lever 86 in a vertically adjustable arm 90 that is pivoted to the member 77 at 91. By raising and lowering this 100 arm 90 about its pivot 91 the pivotal connection 87 for the lever 86 will be raised and lowered, and this will have the effect of raising and lowering the punch. The arm 90 is provided with an opening 92 in which 105 is received a cam 93 that is carried by a shaft 94 which is journaled in the portion 113 of the head 114. The shaft 94 has a handle 115 at one end by which it may be turned. The turning of the shaft and the 110 consequent turning of the cam 93 will operate to raise and lower the arm 90 about its pivot 91 as will be obvious. By this means the punch may be elevated above the sheet or may be lowered into operative position. 115

120 For securing fine adjustments of the punch, I propose to make the portion 113 of the head 114 vertically adjustable. This portion 113 is secured to the head 114 by means of screws 116 which extend through 125 slots in the portion 113, and said portion is also confined between two adjusting screws 117 carried by the head 114. By operating these adjusting screws the portion 113 can be adjusted so as to cause the punch to operate properly.

130 This outlining tool as above described is mounted on a base frame 94 which is independent from the frame 8 and which may be moved into any desired position. The 130

arms 77 and 75 are pivoted on the base frame 94 and can be turned into different angular positions thereon. They are clamped in a desired position by a clamping screw 95 which is actuated by an arm 96.

The master pattern 4 is secured to the pattern supporting table 3 by novel means, which facilitates the placing of the pattern into position or its removal from the support, and which also is constructed to hold the pattern centrally on the table.

The supporting table 3 is provided with a plurality of concentric slots 97, which are equi-distant from each other. Each pattern is adjustably held to the table by two or more clamping bolts 98 which extend through the slots 97. Each bolt is provided with a head 99 engaging the under side of the table and is also provided with a clamping nut 100. A washer 101 is applied to the clamping bolt 98 and rests on the top of the table 3, said washer being large enough to span the slot 97. Two or more clamping bolts are used for securing each pattern in position, and each pattern is provided with an aperture 102 which is large enough to permit the clamping nut 100 to pass therethrough. 103 is a U-shaped washer adapted to be placed between the clamping nut 100 and the pattern 4. Washer 103 covers the aperture 102 in the pattern and provides support for the clamping nut 100 to engage when the latter is tightened.

In securing the pattern to the table, the washers 103 are first removed and the clamping nuts 100 loosened slightly. The pattern is then placed in position on the bolts with the nuts 100 passing through the apertures 102 in the pattern. The bolts are then raised sufficiently to permit the washers 103 to be slipped between the nuts and the pattern, after which the nuts are tightened, thus rigidly clamping the pattern to the table 3.

This construction has the advantage that the pattern can be clamped to the table without entirely removing the nuts 100 from the bolts 98. These bolts, therefore, are always in position, thus obviating any danger of their becoming lost. Moreover it is only necessary to give the nuts 100 two or three turns during the process of securing a pattern to the table or removing it therefrom.

The bolts will preferably be used on opposite sides of the same slot, so that each pattern will be situated substantially centrally of the table 3. The particular slot in which the bolts are used will, of course, depend upon the size of the pattern.

The work support has associated therewith a so-called finder, the purpose of which is to assist the operator in properly placing the sheet material 6 in said work support. This finder comprises a pair of jaws 104 situated above the plane of the sheet material 6 and

between which the pattern may be placed and which are carried by an arm 125 pivotally mounted to the upper jaw 56 as shown at 126. The arm 125 may be conveniently made extensible or adjustable as to its length. 70 This finder is used as follows: A duplicate of the pattern which is to be formed is placed in the jaws 104 and the tracer is brought against the master pattern 4. The sheet material 6 is then adjusted in the 75 work-holding jaws so that the pattern supported by the finder will lie entirely within the outline of the sheet 6, and said sheet may then be clamped into position. This finder indicates the position on the sheet 6 80 from which the pattern will be formed by the operation of the machine, and the finder thus enables the operator to cut various patterns from the single sheet without waste of material and without danger that the 85 patterns will overlap.

It will be noted that the link 48 which connects the upper grading carriage to the lever 42 is situated beneath the carriages. The advantage of this construction is that all the 90 operative connections between the work support and the tracer are located below the carriages and entirely out of the way of the sheet material and of the operator. This enables the machine to operate on a sheet of 95 any size and permits the operator to readily adjust the sheet in the machine without interference from any of the operative parts.

In order that the master patterns 4 may be properly attached to the table 3, it is 100 necessary, of course, that they be provided with properly located apertures 102. In order to facilitate locating these apertures, I propose to use a punch such as illustrated in Figs. 11 and 12. This punch comprises a bed 127 having a die 128 therein and a punch 129 operating in the head 130. The die is provided with an extension 131 having a plurality of apertures 132 therein, into any one of which may be inserted a positioning 110 pin 133. The punch 129 is moved vertically by a screw 134 which is screw-threaded into the head and is provided with a handle 135 for operating it. The extension 131 has a center mark 136 located midway between the punch and the first hole 132. The distance between this punch and the hole 132 is the same as the distance between the opposite sides of the smallest concentric slot 97 in the table 3. 115

In forming the apertures 102 in a master vamped pattern 4, said pattern will be placed in the punch with the center of the pattern and the center line 136 as indicated in dotted lines Fig. 12, and the punch will then be operated to punch one of the holes 102. The pattern is then removed and the punched hole is placed over the positioning pin 133 and after bringing the pattern back to a central position the other hole is punched. This 125 130

locates the two holes properly. For punching larger patterns the positioning pin 133 will be placed in the hole 132 which corresponds to the size of the pattern, and since 5 the distance between the holes and the punch correspond to the distances between the slots 97, a correct location of the holes is always provided.

One feature of my invention to which I 10 desire to call attention is that the movement which is given to the work support is always similar to the movement of the tracer, but in an opposite direction thereto; hence when the tracer is moving in one direction 15 around the edge of the pattern, the work holder will be traveling in a directly opposite direction, this results in inscribing a pattern on the sheet material, any point of which is situated 180° from the correspond- 20 ing point on the master pattern.

Having thus described my invention, what I claim as new and desire to secure by Letters Patent, is:

1. A pattern forming machine comprising pattern-outlining mechanism, work-supporting mechanism, means for supporting a master pattern, a follower, means for moving the same along the contour of said master pattern and means operable thereby to move 25 the work-supporting means relatively to the pattern-outlining means to cause the latter to outline upon the work a design controlled by the configuration of said master pattern.

2. A pattern forming machine comprising 30 outlining mechanism, work supporting mechanism, means for supporting a master pattern, a follower, means for moving the same along the contour of said master pattern, means operable thereby to move the 35 work supporting means relatively to the outlining means to cause the latter to outline upon the work a design controlled by the configuration of said master pattern and adjusting means for varying the amplitude of 40 the movements of the work support to produce patterns varying in size from that of the master pattern.

3. A pattern forming machine comprising 45 outlining mechanism, work supporting mechanism, means for supporting a master pattern, a follower, means for moving the same along the contour of said master pattern, means operable thereby to move the work supporting means relatively to the outlining means to cause the latter to outline upon the work a design controlled by the configuration of said master pattern and adjustable means operable to vary the configuration of the pattern produced from that 50 of the master pattern.

4. A pattern forming machine comprising 55 outlining mechanism, work supporting mechanism, means for supporting a master pattern, a follower, means for moving the same along the contour of said master pattern,

means operable thereby to move the work supporting means relatively to the outlining means to cause the latter to outline upon the work a design controlled by the configuration of said master pattern, adjusting means 70 for varying the amplitude of the movements of the work support to produce patterns varying in size from that of the master pattern and adjustable means operable to vary the configuration of the pattern produced 75 from that of the master pattern.

5. A machine for grading patterns comprising outlining mechanism, a frame, a support for a master pattern sustained thereby, a work support, a duplicating carriage movable longitudinally of the frame, a second duplicating carriage movable transversely of the frame, grading carriages movable longitudinally and transversely of the frame respectively, a follower and means for moving the same along the contour of said master pattern, adjustable means operable by the movement of said follower for imparting to said longitudinally movable grading carriage a differential movement relative to the 90 movement of the longitudinally movable duplicating carriage whereby patterns of different lengths from that of the master pattern may be produced.

6. A machine for grading patterns comprising outlining mechanism, a frame, a support for a master pattern sustained thereby, a work support, a duplicating carriage movable longitudinally of the frame, a second duplicating carriage movable transversely of the frame, grading carriages movable longitudinally and transversely of the frame respectively, a follower and means for moving the same along the contour of said master pattern, adjustable means operable by the movement of said follower for imparting to said transversely movable grading carriage a differential movement relatively to the movement of the transversely movable duplicating carriage whereby patterns of different widths from that of the master pattern may be produced.

7. A machine for grading patterns comprising outlining mechanism, a frame, a support for a master pattern, a work support, a duplicating carriage movable longitudinally of the frame, a second duplicating carriage movable transversely of the frame, grading carriages movable longitudinally and transversely of the frame respectively, a follower and means for moving the same along the contour of said master pattern, independently adjustable means operable by the movement of said follower for imparting differential movements to said longitudinally and transversely movable grading carriages relatively to those of the longitudinally and transversely movable duplicating carriages whereby patterns conforming in configuration to the master pattern, but of 130

different size than the master pattern, may be produced.

8. A machine for grading patterns comprising outlining mechanism, a frame, a support for a master pattern, a duplicating carriage movable transversely of the frame, a second duplicating carriage mounted on the first-named carriage and movable longitudinally of the frame, a grading carriage mounted on said longitudinally movable duplicating carriage, and also movable longitudinally of the frame, a second grading carriage mounted on said longitudinally movable grading carriage and movable transversely of the frame, a work support secured to the transversely movable grading carriage, a follower connected to said longitudinally movable duplicating carriage and means for moving the same along the contour of said master pattern, a lever pivotally mounted upon said longitudinally movable duplicating carriage, means connecting said longitudinally movable grading carriage to said lever, including adjusting means for securing the same to said lever in any position upon either side of said pivot.

9. A machine for grading patterns comprising outlining mechanism, a frame, a support for a master pattern, a duplicating carriage movable transversely of the frame, a second duplicating carriage mounted on the first named duplicating carriage and movable longitudinally of the frame, a grading carriage mounted on said longitudinally movable duplicating carriage and movable transversely of the frame, said latter duplicating carriage having a work support secured thereto, a follower connected to said longitudinally movable duplicating carriage and means for moving the same along the contour of said master pattern, a lever pivotally mounted upon said longitudinally movable duplicating carriage, means connecting said longitudinally movable grading carriage to said lever, including adjusting means for securing the same to said lever in any position upon either side of said pivot, and means for adjusting said lever about said pivot.

10. A grading machine for patterns comprising outlining mechanism, a frame, a support for a master pattern, a duplicating carriage movable transversely of the frame, a second duplicating carriage mounted on the first-named duplicating carriage and movable transversely of the frame, a grading carriage mounted on said longitudinally movable duplicating carriage and movable longitudinally of the frame, a second grading carriage mounted on said longitudinally movable grading carriage and movable transversely of the frame, said latter dupli-

cating carriage having a work support secured thereto, a follower connected to said longitudinally movable duplicating carriage and means for moving the same along the contour of said master pattern, a depending bracket carried by said transversely movable grading carriage and having a pivot thereon, a lever pivotally mounted on said pivot and a link pivotally connected at one end to transversely movable grading carriage and at its opposite end adjustably mounted upon said lever and capable of being secured in adjusted position upon either side of said pivot and means connecting one end of said lever to said base.

11. In a machine for grading patterns, the combination with a base, of means for supporting a master pattern thereon, two superposed duplicating carriages mounted on the base for movement at right angles to each other, a tracer carried by the upper duplicating carriage and adapted to be moved around the contour of the master pattern, two superposed grading carriages mounted on the upper duplicating carriages and arranged to be moved at right angles to each other, a work-holding device carried by the upper grading carriage, and operative connections between said carriages by which a movement of the tracer will produce a similar movement of the work-holding device.

12. In a machine for grading patterns, the combination with a base, of means for supporting a master pattern thereon, two superposed duplicating carriages mounted on the base for movement at right angles to each other, a tracer carried by the upper duplicating carriage and adapted to be moved around the contour of the master pattern, two superposed grading carriages mounted on the upper duplicating carriages and arranged to be moved at right angles to each other, a work-holding device carried by the upper grading carriage, and operative connections between said carriages by which a movement of the tracer will produce a similar movement of the work-holding device but in an opposite direction.

13. In a machine for grading patterns, the combination with a base, of means for supporting a master pattern thereon, two superposed duplicating carriages mounted on the base for movement at right angles to each other, a tracer carried by the upper duplicating carriage and adapted to be moved around the contour of the master pattern, two superposed grading carriages mounted on the upper duplicating carriage and arranged to be moved at right angles to each other, a work-holding device carried by the upper grading carriage, and adjustable operative connections between said carriages by which a movement of the tracer will produce a movement of the work-holder

similar to that of the tracer but of a greater or less amplitude.

14. In a machine for grading patterns, the combination with a base, of means for supporting a master pattern thereon, two superposed duplicating carriages mounted on the base for movement at right angles to each other, a tracer carried by the upper duplicating carriage and adapted to be moved 10 around the contour of the master pattern, two superposed grading carriages mounted on the upper duplicating carriage and arranged to be moved at right angles to each other, a work-holding device carried by the 15 upper grading carriage, and adjustable operative connections between said carriages by which a movement of the tracer will produce a movement of the work-holder similar to that of the tracer but of a greater or less 20 amplitude and in an opposite direction.

15. A pattern forming machine comprising a cutter head, a cutter reciprocably mounted therein and means for actuating the same, a work support, a master pattern 25 and means for moving the work support to present the work to the cutter under the control of the master pattern, and independent means for supporting the cutter head and the work support whereby transmission of 30 the vibration of the cutter to the work support is avoided.

16. A pattern forming machine comprising a cutter head, a cutter reciprocably mounted therein and means for actuating 35 the same, a supporting base for said cutter head, means for adjusting said cutter head upon said base, a work support, a master pattern and means for moving the work support to present the work to the cutter 40 under the control of the master pattern and means for supporting the work support independent of the supporting means for the cutter head.

17. A pattern forming machine comprising 45 means for stationarily supporting a master pattern, a stationarily mounted outlining mechanism, a work-supporting device, and means controlled by the stationary master pattern to move the work supported by 50 the work-support relative to the outlining mechanism, thereby to cause the latter to outline on the work a pattern similar in shape to the master pattern.

18. A pattern forming machine comprising 55 means for stationarily supporting a master pattern, a stationarily mounted outlining mechanism, a work-supporting device, and adjustable means controlled by the stationary master pattern to move the work 60 supported by the work-support relative to the outlining mechanism, thereby to cause the latter to outline on the work a pattern similar in shape to and of the same size as, or of a different size than, the master pattern.

19. In a pattern forming machine, the combination with a main frame, of means for stationarily supporting a master pattern thereon, a follower, means to move the follower around the edge of said master pattern, a work-support, connections between said follower and work-support by which movement of the follower produces a corresponding movement in work-support, and a stationary outlining mechanism mounted independently of the main frame. 75

20. In a pattern forming machine, the combination with a main frame, of means for stationarily supporting a master pattern thereon, a follower, means to move the follower around the edge of said master pattern, a work-support, connections between said follower and work-support by which movement of the follower produces a corresponding movement in the work-support, an 80 outlining mechanism, and a support therefor which is separate from the main frame but capable of being shifted into different positions relative thereto. 85

21. In a pattern forming machine, the combination with a main frame, of means for supporting a master pattern thereon, a follower, a work-support, means to move the follower around the contour of the master pattern, means for causing such movement 90 of the follower to produce a like movement of the work-support, and an outlining mechanism stationarily supported independent of the main frame, but capable of being shifted into different positions relative thereto. 95

22. In a machine for grading patterns, the combination with a base, of two superposed duplicating carriages mounted thereon, superposed grading carriages mounted on the duplicating carriages, a lever pivoted 105 intermediate of its ends to one grading carriage, a block to which said lever is pivoted and which is capable of movement in the direction in which the last named carriage is movable, a link pivotally connected to the other grading carriage, means for securing said link to the lever at any point on either side of its pivotal connection with the grading carriage, means for supporting a master pattern on said base, a tracer connected to 110 one of the duplicating carriages and adapted to be moved around the contour of the master pattern, a work-holding means carried by one of the grading carriages. 115

23. In a machine for forming patterns, the combination with a slotted pattern supporting member, of bolts adjustable in said slots, a clamping nut on each bolt, a master pattern having apertures of a size to permit the nuts to pass therethrough, and washers 120 interposed between the nuts and the master pattern and capable of removal from the bolts in a lateral direction. 125

24. In a machine for forming patterns, the combination with a slotted pattern sup- 130

porting member, of bolts adjustable in said slots, a clamping nut on each bolt, a master pattern having apertures of a size to permit the nuts to pass therethrough, and U-shape
5 washers interposed between the nuts and the master pattern and capable of removal from the bolts in a lateral direction.

25. In a machine for grading patterns, the combination with a base, of a plurality
10 of superposed carriages mounted on said base, some of which are movable in one direction and others of which are movable in a direction at right angles thereto, means to support a master pattern on said base, a
15 tracer carried by one of said carriages and adapted to be moved around the contour of the master pattern, a work-supporting device sustained on the upper carriage, and operative connections between said carriages
20 by which movement of the tracer will produce a similar movement of the work-supporting device, said connections being situated beneath the carriages whereby the space above the carriages is free for the manipulation of the work.

25. In a machine for forming patterns,

the combination with means for holding the material from which the pattern is to be made, a cutting tool comprising a punch, a guide in which said punch reciprocates, a 30 lever connected intermediate of its ends to said punch, a fulcrum block for the lever, means to oscillate the lever and thereby reciprocate the punch, means for raising and lowering the fulcrum of said lever thereby to raise and lower the punch, and means for producing a relative movement between the cutting tool and said material.

27. In a machine for forming patterns, the combination with a work-support for 40 supporting material from which the pattern is to be cut, of a cutting tool comprising a punch, a pivoted lever connected to said punch, means for oscillating said lever above its pivot, a pivoted arm to which the lever is 45 pivoted, and means for raising and lowering said arm thereby to raise and lower the punch.

In testimony whereof, I have signed my name to this specification.

ELMER E. SANBORN.
